FRED R. NEWMAN, OF ST. LOUIS, MISSOURI

DEHAIRING MACHINE

Application filed November 29, 1929. Serial No. 410,397.

The object of my device is to make a dehairing machine particularly adapted to the dehairing of hogs. A more specific object of my device is to provide an auxiliary scraper in a dehairing machine in order to more completely perform the operation in a minimum of time. In the conventional dehairing machine one side of the hog has the bristles removed effectually, and completely, whereas the opposite side of the hog does not have the bristles completely and effectually removed. This is due to the fact that the bristles on one side of the backbone of the hog extend in one direction and those of the other side of the backbone extend in the other direction, that is to say the grain of the bristles is different on one side of the backbone than it is on the opposite side. In order to effectually remove the bristles, the scrapers must scrape against the grain. It is obvious that when the hog is rotated that the scrapers will be presented to the hog against the grain of the bristles only during one-half revolution of the hog. During the other half revolution of the hog, the scrapers move in the direction of the grain of the bristles and press the bristles against the body of the hog rather than scraping them off. Furthermore in the conventional dehairing machine since the hog is not held in position except gravitationally when the scrapers are applied, the hog is thrown in various positions, which prevents the effectual operation of the scrapers. By the use of my auxiliary scrapers, the rotative position of the hog is secured.

My auxiliary scrapers may be made of few and simple parts that lend themselves readily to multiple production and may be easily applied to the conventional machine.

With these and other objects in view, my invention has relation to certain novel features of construction and arrangement of parts as will be hereinafter more fully described, pointed out in the claim and illustrated in the drawings in which

Fig. 1 is a front elevation of a conventional dehairing machine with my attachment applied showing the throw out side of the machine.

Fig. 2 is an end elevation of my device showing the throw in end.

Fig. 3 is an end elevation of my device showing the throw out end.

Fig. 4 is a perspective view of one of the paddles, together with its scrapers forming a part of my auxiliary scrapers.

Fig. 5 is an enlarged end elevation of the cradle used in my device showing the hog in operative position and showing both the conventional scrapers and my auxiliary scrapers.

Numeral 6 designates the frame generally, having the uprights 7 and the cross members 8. Numeral 9 designates the vat of boiling water, from which the hog must be elevated to the dehairing machine. The scalded hog floats in the vat 9. From the vat 9, the hog must be automatically elevated and positioned in the cradle of my device. In the cradle the dehairing operation is performed, after which the hog must be automatically removed from the dehairing machine to a table (not shown) on which the remaining operations on the hog are performed. The dehairing machine generally is described only sufficiently to disclose an operative structure, since my invention is resident in an attachment to the structure and because it is necessary to disclose the entire dehairing machine in order to explain the operation of my attachment. The dehairing machine is power driven.

Numeral 10 designates the drive shaft, which is operatively mounted in the frame 6 as shown in the drawings. A pulley, not shown, is keyed to the drive shaft 10. The power belt is connected to the pulley. By these means the drive shaft 10 is rotated. On the drive shaft 10 is keyed the pinion 11. Numeral 12 designates a gear keyed to the shaft 13, which is rotatively mounted in the frame 6. The gear 12 is in mesh with the pinion 11. On the shaft 13 is keyed the sprocket wheel 14. Numeral 15 designates a second sprocket wheel, which is keyed to the shaft 16, which shaft 16 is operatively positioned at the upper part of the frame 6. Numeral 17 designates an endless chain passing over the sprocket wheel 14 and 15 in oper-

ative relationship. Numeral 18 designates a pinion secured to the shaft 19, which in turn is rotatively secured to the frame 6. The pinion 18 is in mesh with the chain 17 and 5 acts as a tightening means for the chain 17. By the structure thus far described, when the drive shaft 10 is rotated the sprocket wheel 15 will be rotated. On a bracket 20 secured to the frame 6 are positioned hangers 21. In 10 the hangers 21 are rotatively positioned the shaft 22. On the shaft 22 are secured the throw in hooks 23. These hooks are normally in the position shown by the full line in Fig. 2, and project in the vat 9 so that 15 when in the vat 9, the horizontal portion of the hooks will be of such depth in the vat that they will pass under the hog, that is to be thrown into the machine when the hog is moved in the vat on the hook 23. In order 20 to rotate the throw in hook 23 from the position shown in solid line to that shown in dash line that is from the position which the hog assumes in the vat on the hook to the position the hook assumes in throwing the hog into 25 the machine, the shaft 22 must be oscillated. The mechanism for producing this oscillation is the following:

Numeral 24 designates a link secured to the shaft 22. Numeral 25 designates a link secured to the shaft 16. Numeral 26 designates a rod, which is rotatively secured at one end to the end of the link 25 and rotatively secured at its other end to the link 24. It will be seen, therefore, that when the sprocket 30 wheel 15 is rotated in the direction of the arrow shown in Fig. 2 that the rod 26, the links 24 and 25 will assume the position shown in dash line in Fig. 2 and that this position brings the throw in hooks 23 to the position 35 shown in Fig. 2, that is to the throw in position. Obviously after the throw in hooks 23 have been brought to the position shown in the dash line in Fig. 2 and the hog has been thrown into the machine, the throw in hooks 40 23 must be returned to their normal position in the vat 9. Furthermore, it is obvious that it must be necessary to selectively operate the throw in hooks 23 and that this operation must be independent of the continued rotation of the shaft 16.

Numeral 27 designates a clutch operatively positioned on the shaft 16 from which extends the lever 28 and to which is attached the rope 29. When the rope 29 is pulled the clutch 27 operates (by means that is not necessary to describe herein) and the drive shaft 16 is rotated and the throw in hooks 23 oscillated within their limiting positions. When 45 the throw in hooks 23 reach the throw in position, the rope 29 is released and the clutch 27 disengaged and the throw in hooks 23 gravitationally oscillate to their normal position. The hog enters the machine proper in the direction of the long arrow shown in 50 Fig. 2. Numeral 30 designates a series of

hooks, which are secured at intervals to the shaft 31, which is journaled to the frame 6. Between the hooks 30 are rigidly secured a series of grate bars 32. When the hooks 30 are in their normal position they are in the 55 same plane with the grate bars 32 and together form the support for the hog in the machine. While the hog is in this position the scraping is accomplished. On the drive shaft 10 at intervals between the hooks 30 and the grate bars 32 are keyed the webs 33, having the pointed projections 34 to the end of which are secured the web belting paddles 35, near the ends of which are secured the scraper hooks 36. When the scraper hooks 36 are rotated in the direction of the arrow in Fig. 5, they meet the bristles of the hog in the position shown in Fig. 5 and produce a scraping action on the bristles of the hog 60 rotating the hog, but at a much lesser rotation than that of the scraper hooks 36 and when the hog is positioned on one side as shown in Fig. 5, the scraper hooks 36 scrape against the grain of the hog bristles. As the hog is rotated, when the other side of the hog 65 comes in contact with the scraper hooks 36, the hooks will be scraping in the direction of the grain of the bristles and the dehairing 70 will then be imperfect, as previously indicated. Furthermore, unless an upper support is applied over the hog, the hog will in its rotation be moved or bumped up and down vertically in and out of engagement 75 with the scrapers and the dehairing will be imperfect. My auxiliary scrapers act as a 75 support for the hog, preventing this vertical bumping motion as well as presenting scrapers in contact with the hog bristles against the grain of the bristles. The construction of 80 the auxiliary scrapers and support is the following:

Numeral 37 designates a bracket secured to the frame 6, on which is journaled the shaft 38. To the shaft 38 is keyed the link 39. Numeral 40 designates a rod rotatively 85 secured at one end to the free end of the link 39. On the rod 26 is secured the plate 41 forming, together with a portion of the rod 26, a slot into which the end of the rod 40 passes. The disengagement of the rod 40 from this slot is prevented by the nut 42. Numerals 43 designate paddles, which are secured to the shaft 38 in spaced relationship, so as to pass between the grate bars 32 and the brackets 30, when the shaft 38 is 90 oscillated. The paddles 43 are flattened at 44 and bent at right angles to the flattened portion at their free end. To the free ends of the paddles 43 are secured the scraper hooks 45. It will be seen that it is necessary 95 to oscillate the paddles 43 out of the path of the hog in its entry into the machine, otherwise the paddles 43 would be bent or broken or would lie beneath the hog and be inoperative. Therefore, when the hog is 100

thrown on to the grate bars 32 and hooks 30 by the process already described, the paddles 43 must be oscillated to the position shown by dash lines in Fig. 2. This oscillation is 5 accomplished by the movement of the shaft 38. When the rod 40 is pushed to the right in Fig. 2, the paddles 43 will be brought to their operative positions. When the rod 40 is pulled to the left in Fig. 2, the paddles 43 10 will be brought to the dash line position shown in Fig. 2. The movement of the rod 40 to the right or left is accomplished by the movement of the rod 26. It will be seen that the free end of the rod 40 may move in 15 the slot between the plate 41 and the rod 26. When the rod 26 is moved from the position shown in solid lines in Fig. 2 to that shown by dash lines in the same figure, it will be seen that the rod 40 will move to the right or 20 left depending on the direction of the movement of the rod 26. It will be remembered that the rod 26 is the rod that actuates the throw in hooks 23. After the hog has been placed in operative position for dehairing, 25 the paddles 43 must be brought to their operative positions. The paddles 43 must be in the position shown in dash line in Fig. 2 when the throw in hooks 23 are in the position 30 shown by dash lines in the same figure and must remain in that position, until the hog is placed in operative position for dehairing. The throw in hooks 23 must then be placed in the position shown in solid lines in Fig. 2, ready to receive the next hog, and 35 the paddles 43 must be brought to their operative position, that is the position shown by the solid lines in Fig. 2. These two operations are performed by operating the clutch 27. When the throw in hooks are 40 moving to the dash line position in Fig. 2, the rod 40 is pulled to the left and this pull continues until the throw in hooks 23 reach their upper limiting position. Up to this 45 point the power is being applied to the throw in hooks 23, thereby lifting the hog out of the vat 9. After the hog is thrown from the hooks 23, the power is disconnected from the rod 26, by releasing the clutch 27 and the gravitational return of the throw in hooks 50 23 to their normal position pushes the rod 40 to the right in Fig. 2 and moves the paddles to their solid line position in the same figure. After the hog is dehaired, it must be removed from its position on the grate bars 32 55 and the throw out hooks 30. In order to accomplish this, it is necessary to rotate the throw out hooks 30 to the position shown by dash lines in Fig. 3 and this is accomplished by rotating the shaft 31. This latter operation 60 is accomplished by the following structure and in the following manner. Numeral 46 designates a link keyed to the shaft 16. Numeral 47 designates a link keyed to the shaft 31. Numeral 48 designates a rod rotatively secured at one end to the free end of the 65

link 46 and rotatively secured at its other end to the free end of the link 47. Numeral 49 designates a clutch mechanism similar to the clutch mechanism 27 secured to the shaft 16.

Numeral 50 designates a lever connected to the clutch mechanism 49. Numeral 51 designates a rope connected to the lever 50. By means of the rope 51, the link 46 may selectively be made to oscillate, which oscillation through the instrumentality of the link 47 and the shaft 31, oscillates the throw out hooks 31. By this operation, the hog is moved from the position it had when the throw out hooks 30 were in the position shown by the solid lines in Fig. 3 to the position they assume when in the dash line position in the same figure. From the last position, the hog is expelled from the machine gravitationally. The hooks 30 return to 70 their solid line position in Fig. 2 gravitationally. Every alternate paddle 43 is formed without scrapers and bent in the opposite direction of the scraper ends of the remaining paddles in order to prevent a lodging of a 75 hog's foot between adjacent paddles.

What I claim and mean to secure by Letters Patent is:

In combination with a dehauling machine, 80 throw in hooks movably mounted at one side of said machine, a drive rod operatively connected with said hooks to move them to discharge an animal supported thereon into the machine, auxiliary scraper paddles, scraper elements secured to said paddles, a shaft, said paddles secured to said shaft, a link secured to said shaft at one end, a second rod, said link secured at its other end to said second rod, said second rod so connected to said drive rod that said paddles will be moved out of the 85 path of movement of an animal being charged into the machine.

In testimony whereof I affix my signature.

FRED R. NEWMAN.
